UNITED STATES PATENT OFFICE.

WILLIAM S. HEWETT, OF MINNEAPOLIS, MINNESOTA.

REINFORCED-CONCRETE PIPE.

1,413,405.

Specification of Letters Patent. Patented Apr. 18, 1922.

Application filed June 27, 1921. Serial No. 480,633.

To all whom it may concern:

Be it known that I, WILLIAM S. HEWETT, a citizen of the United States, resident of Minneapolis, county of Hennepin, State of Minnesota, have invented certain new and useful Improvements in Reenforced-Concrete Pipe, of which the following is a specification.

My invention relates to reenforced concrete pressure pipe or similar structures wherein the walls are put under tension by hydraulic or pneumatic pressure. It has been customary in the present methods of construction to embed the rods in the concrete in such a manner that the normal shrinkage of the concrete in setting causes compression in the rods and tension in the concrete when the pipe is empty. When the pipe is filled with water or other material under pressure, it tends to expand and further tension is put upon the concrete in the pipe walls, resulting in cracks and leaks. The size of the cracks depends, of course, upon the degree of expansion and outward pressure, but very small cracks resulting from the separation of the particles of concrete will permit the escape of a liquid under pressure in the pipe and impair seriously the efficiency of the pipe as a liquid holding or transporting means. On the other hand, it is well known that concrete in compression is practically water-tight.

The object, therefore, of my invention is to provide a reenforced concrete wall, no part of which shall be under tension even when subjected to hydraulic or pneumatic pressure.

A further object is to provide a reenforced concrete wall in which a considerable saving can be effected in the amount of concrete and steel required to obtain a water-tight structure.

My invention consists generally in placing rods in the wall of a fluid pressure pipe under an initial tension equal approximately to the working stress of the pipe, thereby placing the inner portion of the wall encircled by the rod under compression and preventing the formation of cracks therein when it is subjected to outward pressure or tension.

Further the invention consists in various constructions and combinations, all as hereinafter described and particularly pointed out in the claims.

In the accompanying drawings forming part of this specification,

Figure 1 is an elevation of a reenforced concrete pipe, partially in section, to show the location of the reinforcing rods therein, 60

Figure 2 is a sectional view of the device of Figure 1,

Figure 3 is a sectional view of a joint in the pre-molded reenforced concrete pipe,

Figure 4 is a sectional view through the 65 band of Figure 3.

In the drawing, I have shown a conventional form of reenforced concrete water pipe embodying my invention. It will be understood, however, that I do not confine 70 myself to this structure, as the invention is capable of use wherever it is desired to prevent cracking of concrete under tension.

In the drawings, I have shown a reenforced concrete pipe for conveying water 75 or other liquid under pressure. When this pipe is filled with liquid, the walls of the pipe will be subjected to high tensile stresses. The usual method of constructing such a pipe is to place the reinforcing 80 rods in the concrete when the pipe is moulded. After these pipes are moulded the shrinkage of the concrete in setting causes compression in the steel and tension in the concrete. These stresses are a reversal 85 of the desired stresses as the pipe is designed to withstand pressure with the steel in tension. When water pressure is added the resultant forces cause an additional tension in concrete with the result that the 90 concrete fails and expands until the entire pressure is resisted by the tension in the rods. The high tension in the concrete and its resultant failure causes leaks. The past method of designing pressure pipe has been 95 to use small unit stresses in the steel, about 10,000 pounds per square inch, with the object of reducing the amount of tension on the concrete. But as the stresses caused by shrinkage are larger when a large per 100 cent of steel is used in reinforcing, a small unit stress in steel does not prevent the cracking of the concrete.

I obviate this difficulty by placing the rods under an initial tension so that the 105 inner portion of the walls of the pipe are in compression and in doing this I may employ the following method.

The interior of the pipe lying within the rods as shown at A in Figures 2 and 110

3, is first moulded and allowed to partially set. This allows the shrinkage to take place without causing stresses in the concrete. The rods B (Figures 2 and 3) are then placed with a method provided for adjustment, such as turnbuckles C (Figures 2 and 3). These rods B are then tightened by turning turnbuckles C until they are subjected to the desired initial stress, and this puts the concrete A within the rods in compression. The concrete D lying outside the rods B is then put in place. This coating may be placed by moulding it in forms, by plastering, or by the use of gunite. This outer coating of concrete protects the rods from corrosion, furnishes additional bearing for the rods and provides additional precaution against leakage.

This method of construction also permits a simple method in making joints in pre-moulded reenforced concrete pipe. Figure 3 shows a joint in premoulded pipe using my methods. E and F (Figure 3) are two pieces of pipe to be joined. A band is pre-moulded in sections H (Figures 2 and 4). These sections are then assembled around the pipe and adjustable rods J (Figure 3) are placed and tightened up by the use of turnbuckles C with enough initial tension in said rods to equal or more than equal the pressure to which the pipe is to be subjected. These rods are then buried in concrete placed by any convenient method, such as herein specified for covering the rods in the pipe. A gasket K of lead, felt or other suitable material, may be inserted between the band and the pipe to insure perfect contact.

This method of construction will result in considerable economy. The old method of constructing reenforced concrete pressure pipe called for a low unit stress on steel to avoid high tension in concrete. My invention by avoiding shrinkage stresses will permit a large unit stress in steel resulting in material saving. Under the old method of construction the concrete is always in tension. In my method of construction the concrete is in compression and never in tension. As the allowable unit stress of concrete in compression is more than ten times the allowable unit stress of concrete in tension I make a material saving in concrete.

It should be noted that I make no claim

for invention on the manner of tightening the rods—whether by turnbuckle, by nut and screw end or other method. My claim for invention lies in tightening the rods to a known intensity giving a desired initial stress in the rods before such rods are buried in the concrete. This enables the designer to know that the concrete will not be in tension under any assumed loading. The intensity of the initial stress on the rods may be accurately measured by knowing the length of the lever and power applied in adjustment.

I claim as my invention:

1. A method of reenforcing circular concrete structures which consists in placing separate circular iron or steel bands each with adjustable means, around said structure, and adjusting each band to a known and measured initial stress, and then placing additional concrete imbedding said rods in such manner as to furnish additional bearings for said rods.

2. A method of reenforcing circular concrete structures subject to internal pressure, which consists in placing around a hardened inner core of such structure, separate circular iron or steel bands each with adjustable means, and adjusting each band to a known and measured initial stress of such intensity as to balance internal pressure and then placing additional concrete, imbedding said bands in such manner as to furnish additional bearings for said rods.

3. A method of joining concrete pipe sections which consists in placing the ends of the sections in abutting relation, assembling around the joint a band provided with tightening means then tightening the band to a degree equal or more than equal to the outward pressure to which the pipe will be subjected.

4. A method of joining concrete pipe sections which consists in placing the ends of the sections in abutting relation, assembling around the joint a gasket and around the gasket a band provided with means for tightening the same, then tightening the bands to a degree equal or more than equal to the outward pressure to which the pipe will be subjected.

In witness whereof, I have hereunto set my hand this 22nd day of June, 1921.

WILLIAM S. HEWETT.
